MULTIVALVE CONTROL STATION FOR SERVOMOTORS

Roy R. Stevens, Forest Hills, Pa., assignor to The Westinghouse Air Brake Company, Wilmerding, Pa., a corporation of Pennsylvania

Application January 21, 1947, Serial No. 723,327

14 Claims. (Cl. 121—38)

1

This invention relates to control apparatus and more particularly to the multiple station type.

It is often desired to control operation of a device, such as a variable pitch ship's propeller, by operation of any one of a plurality of operator's control devices located at different control stations, and it is further desirable, at times, that the operating handle of the operator's control device at the non-control station or stations follow movement of and be at all times positioned like the handle of the operator's control device at the selected control station, so that when the control is transferred from one station to another there will be no appreciable change in the adjustment of the device being controlled.

The principal object of the invention is the provision of an improved multiple station control apparatus for accomplishing the above result.

Other objects and advantages will become apparent from the following more detailed description of the invention.

In the accompanying drawings; Fig. 1 is a diagrammatic view, partly in section and partly in outline, of a two station control apparatus embodying the invention; Fig. 2 is a sectional view, at an enlarged scale, taken on line 2—2 in Fig. 1; and Fig. 3 is a diagrammatic view, partly in section and partly in outline of a control apparatus for more than two stations and embodying the invention.

Description—Fig. 1

As shown in Fig. 1, 1 designates a device which it is desired to control; 2, 2a designates two operator's control devices adapted to be located at different control stations for controlling the device 1; 3 designates a selector valve device for selecting the control station; 4 designates a double check valve; and 5, 5a designates two like check valve and choke devices.

Each of the operator's control devices 2, 2a comprises a body 6 and a cover 7 removably mounted on the upper face thereof. Disposed in the body 6 is a self-lapping supply and release valve mechanism 8 comprising a two part casing 9, 9a between which is clamped around its periphery a flexible diaphragm 10. The diaphragm 10 and the casing part 9 define a control chamber 11 at one side of the diaphragm and the diaphragm together with the casing part 9a defines a chamber 12 at the opposite side, the chamber 12 being open to atmosphere through an opening 13. Mounted in chamber 11 against one side of the diaphragm is a follower 14 having a stud portion 15 extending centrally through said diaphragm into chamber 12 and also extending centrally through a follower 55

2

plate 16 disposed in chamber 12 in contact with the opposite side of the diaphragm. A nut 17 on the stud portion 15 is tightened against the follower plate 16 for securely clamping said plate and the follower 14 to opposite sides of the diaphragm. A control spring 18 contained in chamber 12 has one end bearing against the follower plate 16 while the opposite end is supported on a spring seat 19. The seat 19 is in turn supported on one end of an adjusting screw 20 having screw-threaded engagement with the casing part 9a and extending to the exterior thereof.

The casing part 9 has a bore open to chamber 11 in coaxial relation with the diaphragm 10, and slidably mounted in this bore adjacent the diaphragm is a cylindrical extension 21 of the diaphragm follower 14. Slidably mounted in the bore above the extension 21 is a relatively movable plunger or piston 22 one end of which cooperates with said extension to form a pressure chamber 23 which is open to a control pipe 24 and through a restricted port 25 with chamber 11. The follower 14 and stud portion 15 and extension 21 thereof have an axial bore 26 open at one end to chamber 23 by way of a cavity 27 in said extension and open at the opposite end to a cross bore 28a opening to chamber 12. Contained in cavity 27 is a fluid pressure release valve 28 arranged to seat on extension 21 for closing communication between said cavity and chamber 23, and the bore 25.

The plunger or piston 22 has an internal chamber 29 open through one or more radial bores 30 to an annular cavity 31 provided in the exterior surface of said piston. The cavity 31 is open to a fluid pressure supply pipe 32. The chamber 29 is also open through an axial bore in piston 22 to chamber 23 and contains a fluid pressure supply valve 33 arranged to cooperate with the piston 22 around the adjacent end of said bore to close communication between said chamber and bore, said valve being connected to one end of a pin 34 loosely extending through said bore into chamber 23 wherein the release valve 28 is connected to the opposite end of said pin. A bias spring 35 contained in chamber 29 acts on the supply valve 33 for urging it to its closed position. A spring 36 contained in chamber 23 acts on adjacent ends of piston 22 and the diaphragm follower extension 21 for urging said piston in a direction away from said extension.

A follower finger 37 having one end fulcrumed on a pin 38 carried by the body portion 9 has one side of its opposite cylindrical like end engaging the end of the piston 22 which projects from the

body portion 9a. The other side of the cylindrical like end of finger 37 is engaged by an adjustable arcuate shaped cam element 39 pivotally connected at one end by a pin 40 to a hub 41 of an operator's lever 42, said hub being journaled on a shaft 43 carried by the body 6 directly above the upper end of piston 23 and with its axis at right angles to that of said piston. The opposite end of the cam element 39 has a slot in which is disposed an eccentric portion 44 of an adjusting screw 45 extending through the hub 41 from side to side and having on one end a head 46 engaging one side of said hub and on the other end a lock nut 47 for engaging the opposite side.

The cover 7 has a slot 48 extending transversely of shaft 43 through which the lever 42 extends to the exterior of the control device.

Disposed in the casing 6 of the control device at one side of the operator's control lever hub 41, is a structure 49 for holding said lever against accidental movement by vibration or the like. This structure 47 comprises a casing containing a flexible diaphragm 50 clamped around its edge and cooperating with the casing to form at one side a control chamber 51 open to pipe 32 and to form at the opposite side a chamber 52 open to atmosphere. Secured to the center of diaphragm 50 and projecting therefrom through chamber 52 into a bore in the casing is a plunger 53 arranged at one side of the hub 41 at right angles to the axis thereof. In this bore is also slidably mounted a friction shoe 54 having on one end an arcuate surface which is arranged to slidably and frictionally contact the peripheral surface of hub 41. The shoe 54 has a cross slot open to the opposite end thereof, and carried by the casing and extending through this slot is a pin 55 for holding the arcuate surface of the shoe in working alignment with the peripheral surface of the hub. A spring 56 acts on diaphragm 50 for urging same and plunger 53 in a direction away from hub 41 to permit disengagement of shoe 54 from said hub.

The casing part 9 of the supply and release valve mechanism 8 has an open ended chamber in which is slidably mounted a fulcrum piston 57 of a fulcrum device 105. The piston 57 has a hollow rod 58 mounted to slide in a bore provided axially through a stop member 59 secured in the open end of said bore. The face of piston 57 from which rod 58 extends is open to atmosphere through clearance space (not apparent in the drawing) between said rod and the wall of the bore through member 59 and a felt dust excluding ring 60 carried by said member and having sliding contact with the surface of said rod. At the opposite side of piston 57 is a control chamber 61 open to a pipe 62.

A fulcrum pin 63 is carried in the end of the fulcrum piston stem 58 and a lever 64, intermediate its ends, is fulcrumed on said pin. One end of lever 64 is in the form of a screw-threaded stud 65 and adjustably mounted on this stud is a clevis 66 and a lock nut 67 for engaging the end thereof for locking it in an adjusted position on said lever. Connected to the opposite end of clevis 66 by a pin 68 is one end of a link 69 the opposite end of which is connected to the adjustable cam fulcrum pin 40.

The opposite end of lever 64 is pivotally connected by a pin 70 to one end of a screw-threaded member 71 upon which is adjustably mounted a clevis 72 and a lock nut 73 for engaging one end of said clevis for securing same on said member in an adjusted position. The opposite end of

clevis 72 is pivotally connected by a pin 74 to one end of a rod 75 projecting from a repeater or follow-up motor device 76.

The repeater motor device 76 comprises a casing containing a flexible diaphragm 77 clamped around its periphery in the casing in coaxial relation with the rod 75 which is secured to the center of said diaphragm by followers 78 and 79 engaging opposite faces of the diaphragm, a shoulder 80 on said rod engaged by the follower 78 and a nut 81 on said rod engaging the follower 79. The follower 79 is contained in a pressure chamber 82 open to pipe 62. The follower 78 is contained in a chamber 83 which is open to atmosphere through a passage 84. Two precompressed coil springs 85 and 86 contained in chamber 83 and encircling the rod 75 therein bear at one end against the follower 78 for urging the diaphragm 77 and followers 78 and 79 in the direction of one or more stops 103 provided for contact by follower 79. The opposite end of spring 85 is supported on a wall of chamber 83, while the opposite end of spring 86, which is disposed within spring 85, is supported on an adjustable spring seat 87 which in turn is supported on an adjustable stud 88 having screw-threaded engagement with the casing. The spring seat 87 and stud 88 are centrally apertured through which apertures the rod 75 extends to the exterior of the casing. A lock nut 89 on stud 88 is provided for contact with the casing to secure the stud 88 in an adjusted position.

The selector valve device may, for the purpose of illustration, comprise a casing to which are connected pipes 90 and 91, and a fluid pressure supply pipe 92 adapted to be supplied with fluid under pressure from any suitable source. A plug valve 93 mounted in the casing is arranged to be turned by a handle 94 to either of two positions, one position being that in which it is shown and the other being indicated by a line 95. The plug valve 93 has two cavities 96 and 97, the cavity 96 being provided for connecting pipe 90 to the fluid pressure supply pipe 92 when handle 94 is in the position shown in the drawing, and to connect pipe 90 to an atmospheric vent passage 98 in the other position of said handle. Cavity 97 is provided for connecting pipe 91 to vent passage 98 with handle 94 in the position shown in the drawing and to the fluid pressure supply pipe 92 with said handle in its other position.

The two check valve and choke devices 5, 5a are of identical structure, each comprising a casing containing a check valve 99 for permitting flow of fluid under pressure in a direction from an inlet 100 to an outlet 101 but to prevent reverse flow by way of said check valve. The casing also has a communication by passing the check valve 99 and containing a choke 102 for restricting flow of fluid under pressure in a direction from the outlet 101 to the inlet 100.

The check valve and choke device 5 connects pipe 90 to pipe 32 leading to the operator's control device 2 in such a manner as to permit relatively rapid flow of fluid under pressure in the direction to said pipe 32 past the respective check valve 99 but to restrict flow in the opposite direction through choke 102, while the check valve and choke device 5a so connects pipe 91 to pipe 32 leading to the operator's control device 2a as to permit relatively rapid flow of fluid under pressure in the direction from pipe 91 to said operator's control device and restricted flow in the reverse direction.

Operation—Fig. 1

Let it be assumed that the adjustable cam 39, the connection therebetween and diaphragm 77 in the repeater motor 76 and the stud 88 in said motor are all properly adjusted in each of the operator's control devices and that the adjustments in both of said control devices are identical. Let it further be assumed that it is desired to control the device 1 from the operator's control device 2 and prevent control by the operator's control device 2a. To accomplish this, the handle 94 and valve 93 of the selector valve device will be turned to the position shown in the drawing for opening pipe 91 to atmosphere and for connecting pipe 90 to the fluid pressure supply pipe 92.

Now assume that fluid under pressure is supplied to pipe 92 and thence to pipe 90 from which it will flow past check valve 99 in the check valve and choke device 5 and thence through pipe 32 to diaphragm chamber 51 in the structure 49 and to the inlet valve chamber 29 in piston 22 of the supply and release valve mechanism 8 of the operator's control device 2.

The fluid under pressure thus supplied to chamber 51 in structure 49 of the operator's control device 2 will deflect diaphragm 50 against spring 56 and press the brake shoe 54 in frictional contact with the hub 41 of the operator's lever 42 with sufficient force to hold said lever in any position against accidental movement therefrom due for example to vibration.

With the operator's control lever 42 of the valve device 2 in the position shown in the drawing, the cam 39 will be adjusted to hold the piston 22 in the position shown in the drawing, and with no fluid pressure in chamber 11 above diaphragm 10, spring 18 will deflect said diaphragm to a position defined by contact between the diaphragm follower 14 and a shoulder 104 in the casing part 9, in which position the release valve 28 will be seated and through the pin 34 the supply valve 33 will be unseated. When fluid under pressure is supplied to the inlet valve chamber 29 as above described, fluid will then flow therefrom past the supply valve 33 to chamber 23 and thence to pipe 24 and through choke 25 to chamber 11 above diaphragm 10. The pressure of fluid thus obtained in chamber 11 will, as it increases, deflect the diaphragm 10 against spring 18 and permit the supply valve 33 to move toward its seat, and this action will continue until said valve becomes seated in a position determined by the position of piston 22. When the supply valve 33 seats as just described it will prevent further flow of fluid under pressure to chambers 23, 11 and the connected pipe 24, thereby limiting the pressure obtained therein to a chosen preselected degree, such as ten pounds, corresponding to the position of piston 22 and adjustment of cam 39 with the operator's control lever in the position in which it is shown in the drawing.

Fluid under pressure thus supplied by the operator's control device 2 to the connected pipe 24 will flow through said pipe, past the double check valve 4 to the device 1 for controlling same, and will also flow from said pipe through the pipe 62 leading to the operator's control device 2a and to chambers 61 and 82 in the respective fulcrum device 105 and repeater motor 76. This pressure acting on piston 57 in the fulcrum device 105 in the operator's control device 2a will move said piston into contact with the adjacent end of stop member 59, which position it will always occupy when subject to pressure of fluid at or exceeding

the pressure provided in the delivery pipe 24 connected to the operator's control device 2. The pressure of fluid obtained in chamber 82 of the repeater motor 76 of the operator's control device 2a from the operator's control device 2 with its lever 62 in the position shown in the drawing will just balance the opposing pressure of the respective springs 85, 86 on diaphragm 97, so that said springs will be able to hold the follower 79 just in contact with the stop 103. With the piston 57 of fulcrum device 105 and diaphragm 97 of the repeater motor 76 in the operator's control device 2a positioned, as just described, by fluid under pressure supplied from the operator's control device 2 with its control lever 42 in the position shown in the drawing, the lever 42 in the operator's control device 2a will be caused to assume the same position.

When the selector valve device 3 is adjusted to render the operator's control device 2 effective and the operator's control device 2a ineffective to control the device 1, the pipe 81 is opened to atmosphere as above mentioned, and as a result, diaphragm chamber 51 and the supply valve chamber 29 in the operator's control device 2a will likewise be opened to atmosphere. In the operator's control device 2a, the diaphragm 50 in structure 49 will therefore be deflected in a direction to relieve pressure of the shoe 54 against hub 49 of the operator's lever to permit free movement of said lever, while opening the supply valve chamber 29 to atmosphere will, with the piston 22 and lever 42 in the position shown in the drawing, permit the supply valve 33 to be open for connecting diaphragm chamber 14 and the connected pipe 24 to the respective pipe 32 and thus to atmosphere. With the pipe 24 connected to the operator's control device 2a thus open to atmosphere, chamber 61 in the fulcrum device 105 and diaphragm chamber 82 in the repeater motor 76, in the operator's control device 2 will also be open to atmosphere through the respective pipe 62 and said pipe 24.

Summarizing, it will be noted that when the operator's control device 2 is selected for controlling the device 1, the friction shoe 54 therein is rendered effective, the supply and release valve mechanism 8 therein is supplied with fluid under pressure from the supply pipe 92 and controls supply of fluid under pressure to the device 1, while chambers 61 and 82 in the fulcrum device 105 and repeater motor 76 therein are open to atmosphere, and with the respective operator's control lever 42 in the position shown in the drawing, the respective fulcrum piston 57 will just contact the inner end of stud 59, while diaphragm follower 79 of said repeater motor will just contact the stop 103. On the other hand, in the operator's control device 2a, the brake shoe 54 is ineffective, no fluid under pressure is supplied to the supply and release valve mechanism 8, the fulcrum piston 57 will be urged into contact with the adjacent end of stop member 59 by pressure of fluid supplied by the supply and release valve mechanism 8 in the operator's control device 2, and diaphragm 77 in the repeater motor 76 will be subject in chamber 82 to pressure of fluid supplied by said mechanism, which pressure will just balance that of springs 85 and 86 with the diaphragm follower 79 in contact with stop 103, said diaphragm and follower and the fulcrum piston 57 therefore occupying the same positions as the corresponding parts in the operator's control device 2, and when so positioned, the connections between lever 64 and the adjustable cam 39

and rod 75 in the repeater motor 76 in the operator's control device 2a will be adjusted to cause the respective lever 42 to occupy the same position as the operator's lever 42 in the operator's control device 2.

Now let it be assumed that lever 42 of the operator's control device 2 is turned clockwise out of the position in which it is shown, to any chosen degree. This movement will be resisted by pressure of friction shoe 54 which however upon cessation of such movement will securely hold the lever 42 in the chosen position. As the lever 42 in the operator's control device 2 is thus turned in a clockwise direction, the lever 64 due to its connection with cam 39 will be turned in a counter-clockwise direction about its connection at pin with the repeater motor 76, the parts of which will remain in the position shown in the drawing due to the action of springs 85 and 86. As a result, the fulcrum piston 58 will be moved by the lever 64 out of contact with stop 59, and since chamber 61 is open to atmosphere, this movement of piston 57 will be unopposed. It will thus be seen that in the operator's control device 2 the lever 64 and piston 57 simply idle upon movement of lever 42, and it is to be noted that the space below piston 57 is sufficient to permit movement through the full range of movement of lever 42 from the position in which it is shown to the opposite end of the slot 48.

When lever 42 in the operator's control device 2 is operated as just described, the cam 39 will move the piston 22 in the direction of diaphragm 10 an amount proportional to the extent of movement of said lever, and this movement of said piston will initially be relative to the diaphragm 10, and hence the supply valve 33 which will initially be held stationary by the control spring 18 acting in said diaphragm. As a result, the piston 22 will be moved out of contact with the supply valve 33 whereupon fluid under pressure will flow past said valve to chamber 27 and thence to the connected pipe 24 and from said pipe past the double check valve 4 to the device 1 for adjusting said device.

As fluid under pressure is thus flowing to the device 1 from the operator's control device 2 it will also become effective through choke 25 in chamber 11 above diaphragm 10 and deflect said diaphragm against spring 18 and this deflection and consequent movement of the supply valve 33 therewith will continue until said valve seats to prevent further flow of fluid under pressure to the device 1 for limiting the pressure therein to a degree corresponding to the position of piston 22 and in turn the position of lever 42.

Fluid under pressure thus supplied by the operator's control device 2 to the connected pipe 24 for controlling operation of the device 1 also flows through the pipe 62 connecting said pipe 24 to the operator's control device 2a to piston chamber 61 in the fulcrum device 105 therein for holding the respective fulcrum piston 57 against stop 59, and also to diaphragm chamber 82 of the respective repeater motor 76. The pressure of fluid thus obtained in chamber 82 in the operator's control device 2a will deflect the diaphragm 77 against springs 85 and 86 to a position in which the pressure of said springs will be increased sufficiently to counterbalance the pressure of fluid, and this movement will actuate lever 64 to turn lever 42 of the operator's control device 2a to a position corresponding to that of the actuating diaphragm 77. The connections between lever 64, the adjustable cam 39 and rod 75

75 of the repeater motor 76 will be so adjusted, and the pressure of spring 86 will be so regulated by the adjusting stud 88, that for the position assumed by the diaphragm 77 in response to pressure of fluid provided in chamber 82 by operation of the operator's control device 2, the lever 42 of the operator's control device 2a will be moved to the same position as occupied by lever 42 of the operator's control device 2.

10 Now assume that the lever 42 of the operator's control device 2 is moved further in a clockwise direction for increasing the pressure of fluid in the device 1 to be controlled. This increased pressure will become effective in the repeater motor 76 of the operator's control device 2a to cause the respective lever 42 to assume the same position as that of the operator's control device 2.

Assume that the lever 42 of the operator's control device 2 is occupying a position to the right of that shown in the drawing for supplying fluid at a chosen pressure to the device 1, and that it is desired to reduce this pressure. To accomplish this, the lever 42 of the operator's control device 2 will be moved in a counterclockwise direction to a position corresponding to the pressure desired in device 1.

In the operator's control device 2, this movement of lever 42 and consequently of cam 39 will permit the piston 22 to be moved upwardly by

30 spring 36 and pressure of fluid in chamber 23, and with the supply valve 33 seated as previously described, said valve will move with said piston and pull the release valve 28 off of its seat, since at this time said seat will be held stationary with 35 diaphragm 10 by pressure of fluid acting in chamber 11 on said diaphragm. Upon opening the release valve 28, fluid under pressure will then flow from chamber 23 and the connected pipe 24 and device 1 to atmosphere, and the 40 pressure of fluid in diaphragm chamber 11 will reduce with that in chamber 23. As the pressure in chamber 11 thus reduces, spring 18 will deflect diaphragm 10 and consequently the seat for the 45 release valve 28 upwardly, and this movement will continue until the pressure of fluid controlling the device 1 becomes reduced sufficiently to permit the seat for the release valve to be moved into engagement therewith, for thereby limiting the reduction in pressure in chambers 23 and 50 11, and in the device 1 to a degree corresponding to the position of said release valve, and hence corresponding to the position of piston 22 and lever 42 of the operator's control device 2.

As the operator's control device 2 thus operates 55 to reduce the pressure of fluid supplied thereby to a degree corresponding to the change in position of the respective lever 42, a corresponding reduction in pressure of fluid occurs in chamber 82 in the repeater motor 76 of the operator's control 60 device 2a which permits springs 85 and 86 in said motor to actuate diaphragm 77 to move the respective operator's lever to a new position, corresponding to said reduction in pressure of fluid and hence corresponding to the new position 65 of lever 42 in the operator's control device 2.

It will now be seen that regardless of the position to which the lever 42 in the operator's control device 2 is moved, the repeater motor 76 in the operator's control device 2a will move lever 42 of the operator's control device 2a substantially in unison and to a corresponding position.

If it is desired that the control station be changed from the operator's control device 2 to the operator's control device 2a, the selector 75 valve device 3 is operated to its other position for

opening pipe 90 to atmosphere and for supplying fluid under pressure to pipe 91.

The opening of pipe 90 to atmosphere will release fluid under pressure from diaphragm chamber 51 in the structure 49 in the operator's control device 2 for rendering the respective brake shoe ineffective, and will also result in release of fluid under pressure from the respective supply valve chamber 28. Pressure of fluid in chamber 23 in the operator's control device 2 will then blow the supply valve 33 from its seat against the small resistance of spring 35, and be dissipated along with that in the connected pipes 24 and 62 and in the fulcrum piston chamber 61 and repeater diaphragm chamber 82 in the operator's control device 2a. In the operator's control device 2a the parts of the repeater portion 76 will therefore assume the position shown in the drawing and the fulcrum piston 57 will be freed to move with the control lever 42.

When fluid under pressure is supplied to pipe 91 by turning the selector valve 3 as above mentioned, the supply and release valve mechanism 8 in the operator's control device 2a will operate to supply fluid under pressure to the connected pipe 24 and thence by way of the pipe 62 connected to the operator's control device 2 to the fulcrum piston chamber 61 and repeater diaphragm chamber 82 therein. The pressure obtained in chamber 61 in the operator's control device 2 will move the respective piston 58 to the position shown in the drawing to provide a fulcrum for the connected lever 64 for rendering the respective repeater portion 76 effective to adjust the position of the respective operator's control lever 42 in accordance with pressure of fluid provided in chamber 82 of said repeater portion.

From the above description it will be evident that with the apparatus conditioned as just described, providing for control of device 1 by the operator's control device 2a, the lever 42 of the operator's control device 2 will follow movement of lever 42 of the operator's control device 2a and always assume a corresponding position.

When the selector valve device 3 is operated to transfer the control station to the operator's control device 2a, it will be noted that choke 102 in the check valve and choke device 5 restricts release of fluid under pressure from diaphragm chamber 51 in the structure 49 of the operator's control device 2, and at the same time the pressure of fluid supplied to pipe 91 is permitted to flow at a relatively rapid rate to the corresponding chamber in structure 49 of the operator's control device 2a. The purpose of this is to ensure that the brake shoe 54 in the operator's control device 2a at the new control station, will become effective before the corresponding brake shoe, at the station from which control is being removed, becomes ineffective, in order to ensure against any accidental change in position of the operator's control levers 42 during this change in control stations. The choke 100 in the check valve device 5a functions in a like manner in changing control stations from the operator's control device 2a to the operator's control device 2.

Before the operator's control devices 2 and 2a are operated, as above described, certain adjustments are required to ensure that the pressure of fluid supplied by both of said devices to the respective pipes 24 will be the same for the same positions of the operating levers 42. To effect these adjustments, the lever 42 of each device will be moved to the right hand end of the respective slot 48, and assuming that the supply

valve chamber 29 is supplied with fluid under pressure, the screw 20 is then adjusted to regulate the pressure of spring 18 against the diaphragm 10 until the pressure obtained in chamber 23 and the connected pipe 24 (as registered on a gage) is of the desired degree, such as 90 pounds. After this adjustment is completed, the lever 42 is moved to the left hand end of slot 48, and the screw 45 with the eccentric portion 44 is turned to adjust this end of the cam 39 and the position of piston 22 until the pressure in chamber 23 and the connected pipe 24 is at the desired minimum degree, such as the 10 pounds above described. With the two operator's control devices 2 and 2a thus adjusted to provide the same pressures in the respective pipes 24 in the two extreme positions of the respective levers 42, and with identical cams 39, the pressure of fluid provided in pipes 24 of the two control devices 2, 2a will be the same for all identical positions of the two operator's control levers 42.

Description—Fig. 3

The invention as embodied in the structure shown in Fig. 1 is limited to two control stations or two operator's control valve devices 2, 2a, but if desired, may be extended to any desired number of control stations in the manner shown in Fig. 3 wherein it is shown applied to three control stations.

As shown in Fig. 3, 2, 2a designates operator's control devices, like those shown in Fig. 1, adapted to be located at two control stations, while 2b designates a like operator's control device for the third stations. 5 and 5a and 4 designate check valve devices and chokes like those required for the two station control, while 5b and 4a indicate like devices required in connection with the additional control station where the operator's control device 2b is located. Reference numeral 106 designates a selector valve device having three positions, corresponding to the number of control stations and operative in each different position to supply fluid under pressure from the fluid pressure supply pipe 92 to the pipe 90, 91 or 91a leading to the operator's control device 2, 2a or 2b which is selected to control the device 1, while at the same time opening to atmosphere the other two of said pipes.

According to this modification, an intercepting valve device 107 is provided at each control station. The intercepting valve device comprises a casing having a chamber 108 containing a valve 109 arranged to control communication between said chamber and chambers 110 and 111. Chamber 111 is open to atmosphere through a passage 112 and is formed at one side of a piston 113 at the opposite side of which is a control chamber 114. When fluid under pressure is supplied to chamber 114, the piston will operate valve 109 to close communication between chambers 108 and 110 and to open chamber 108 to atmosphere through chamber 111 and passage 112. When chamber 114 is void of fluid under pressure a spring 115 in chamber 110 will move valve 109 to the position shown for disconnecting chamber 108 from chamber 111 and for connecting chamber 108 to chamber 110.

At each control station chamber 108 is connected to pipe 62 from the respective operator's control device 2, 2a or 2b, while chamber 114 is connected to the fluid pressure supply pipe 90, 91 or 91a leading to said operator's control device. Chambers 110 in all of the intercepting valve devices 107 are connected together by a pipe 116 and

11

to the pipe connected to the device 1 to be controlled.

In operation, assume that the selector valve device 106 is in the position shown in the drawing supplying fluid under pressure to pipe 90 and opening pipes 91 and 91a to atmosphere. Fluid under pressure will then flow through pipe 90 to the operator's control device 2, selected for controlling operation of the device 1, and in said operator's control device the brake shoe 54 will be rendered effective and the supply and release valve mechanism 8 will be rendered effective upon movement of the lever 42 to supply fluid to the respective pipe 24 at a pressure corresponding to the position of said lever. Fluid under pressure thus supplied by the operator's control device 2 to the respective pipe 24 will then flow through the double check valve 4, a pipe 111, and through the double check valve device 4a to the device 1 for actuating same.

Fluid at the pressure thus supplied to the device 1 will become effective through pipe 116 in chamber 110 of all of the intercepting valve devices 107. In the intercepting valve device 107 connected to the operator's control device 2, pressure of supply in pipe 90 is effective in chamber 114 to actuate piston 113 for actuating the valve 109 to the position for closing communication between chambers 108 and 110 and for opening the former chamber to atmosphere. Hence, chamber 61 in the fulcrum device 105 and chamber 82 in the repeater motor 76 in the operator's control device 2 at the control station will be open to atmosphere, the same as in the structure shown in Fig. 1.

Pipes 91 and 91a being both open to atmosphere in the position of the selector valve device 106 providing for control of the apparatus by the operator's control device 2, the brake shoe 54 in the operator's control devices 2a and 2b will be rendered ineffective, and the piston chambers 114 in the intercepting valve devices 107, associated with the operator's control device 2a and 2b at the non-control stations, will also be open to atmosphere permitting each of the respective valves 109 to close communication between chambers 108 and 111 and to open chamber 108 to chamber 110. As a result, fluid under pressure supplied by the operator's control device 2 at the control station for operating the device 1 and supplied to chamber 110 in the intercepting valve devices 107 at the two non-control stations, will flow from said chamber through the respective pipe 62 to actuate the fulcrum piston 57 in each of said devices to the position shown in Fig. 1, and to become effective in diaphragm chamber 82 of the respective repeater motor 76, whereby upon operation of the lever 42 of the operator's control device 2 at the selected control station the levers 42 of the operator's control devices 2a, 2b at the non-control stations will follow and always occupy the same position as that occupied by said lever at the control station.

Now assume that it is desired to transfer the control of device 1 from the operator's control device 2 to the operator's control device 2a. To accomplish this the selector valve device 106 will be moved to the position for connecting pipe 91 to the fluid pressure supply 92 and for opening pipes 90 and 91a to atmosphere. The brake shoe 54 in the operator's control device 2a will therefore be rendered effective; and the intercepting valve device 107 associated with the operator's control device 2a will operate to open to atmosphere the respective pipe 62 and thereby the con-

12

nected fulcrum piston chamber 61 and repeater motor diaphragm chamber 82. The operator's control device 2a is now effective to control the device 1. The intercepting valve devices 107 associated with the operator's control devices 2, 2b, at the non-control stations, will however remain in the position shown in the drawing to permit fluid under pressure supplied by the operator's control device 2a for controlling the device 1 to become effective in the fulcrum piston chambers 61 and repeater motor diaphragm chambers 82 of the operator's control devices 2a, 2b so that the control levers 42 thereof will move with and assume positions corresponding to the control lever 42 of the operator's control device 2a.

In a similar manner, if it is desired to employ the operator's control device 2b for controlling the device 1, the selector valve device 106 will be operated to open pipe 91a to the supply pipe 92 and to open to atmosphere the pipes 90 and 91, whereby the intercepting valve devices 107 will be adjusted to cause the levers 42 of the operator's control devices 2, 2a to move with and always occupy the same position as the lever 42 of the operator's control device 2b at the control station.

Summary

It will now be seen that I have provided in a multiple control station apparatus embodying an operator's control device at each station and means for selectively rendering any one of said devices effective and all others ineffective for controlling a desired operation, and structure which is operative, regardless of the selected control device, to cause the control levers of the ineffective control devices to move with and always assume the same position as occupied by the control lever of the selected device.

Having now described my invention, what I claim as new and desire to secure by Letters Patent, is:

1. In combination, two operator's control means each comprising a lever having a zone of movement, self-lapping controlling structure operative by movement of said lever in said zone, and repeater means controlled by said structure in the other control means for automatically positioning the respective lever in accordance with the position of the other lever, and other means for selectively rendering the structure of either control means effective to control the repeater means in the other control means and for at the same time rendering the other structure ineffective.
2. In combination, two operator's control means each comprising a lever having a zone of movement, holding means adapted to cooperate with said lever for holding it in any desired position, self-lapping controlling structure operative by movement of said lever in said zone, and repeater means controlled by said structure in the other control means for automatically positioning the respective lever in accordance with the position of the other lever, and other means for selectively rendering the structure of either control means effective to control the repeater means in the other control means and for at the same time rendering the other structure ineffective, each control means further comprising means responsive to operation of said other means for rendering said holding means effective and ineffective upon rendering the respective control means effective and ineffective, respectively.
3. In combination, two operator's control means each comprising a manually operable lever

having a zone of movement, self-lapping valve means operable by said lever in said zone to supply fluid at a pressure corresponding to the position of said lever in said zone, and repeater means adapted to be operated by fluid at a pressure corresponding to any position of said lever in said zone to move said lever to said position, and means for selectively rendering either valve means effective to supply fluid under pressure to the repeater means in the other control means and for at the same time rendering the other valve means ineffective to supply fluid under pressure to the other repeater means.

4. In combination, two fluid pressure supply pipes, two fluid pressure control pipes, two operator's control means each comprising a manually operable lever having a zone of movement, and valve means operable by said lever to supply fluid from one of said supply pipes to one of said control pipes at a pressure corresponding to the position of said lever in said zone, selector means for selectively supplying fluid under pressure to either one of said supply pipes and for at the same time opening the other supply pipe to atmosphere, each control means being also operable to release fluid under pressure from the respective control pipe to the respective supply pipe upon opening the last named pipe to atmosphere, and each control means further comprising repeater means arranged to be responsive to pressure of fluid in the control pipe connected to the other control means and operative upon supply of fluid under pressure to the last named pipe to position the respective lever in the zone in accordance with the pressure of such fluid.

5. In combination, a device to be controlled, two operator's control means each comprising a lever having a zone of movement, and valve means operable by said lever to supply fluid at a pressure corresponding to the position of said lever in said zone, means for conveying fluid under pressure from said control means to said device comprising a double check valve operable by fluid under pressure supplied by either control means to open communication therebetween and said device and for closing communication between said device and the other control means, each control means further comprising repeater means adapted to be operated by fluid under pressure for moving the respective lever to a position corresponding to the pressure of such fluid, selector means for selectively rendering either of said valve means effective to supply fluid under pressure and the other ineffective, and means controlling a fluid pressure supply communication between said device and each repeater means operable upon operation of said selector means to render either of said control means effective to close the fluid pressure supply communication to the respective repeater means and to open the fluid pressure supply communication to the other repeater means.

6. In combination, two fluid pressure supply pipes, two fluid pressure control pipes, two operator's control means each comprising a manually operable lever having a zone of movement, and valve means operable by said lever to supply fluid from one of said supply pipes to one of said control pipes at a pressure corresponding to the position of said lever in said zone, selector means for selectively supplying fluid under pressure to either one of said supply pipes and for at the same time opening the other supply pipe to atmosphere, each control means being also operable to release fluid under pressure from the respective control pipe

to the respective supply pipe upon opening the last named pipe to atmosphere, each control means further comprising repeater means arranged to be responsive to pressure of fluid in the control pipe connected to the other control means and operative upon supply of fluid under pressure to the last named pipe to position the respective lever in its zone in accordance with the pressure of such fluid, a fluid pressure adjustable device, and means connecting said control pipes to said adjustable device for conveying fluid under pressure thereto for adjusting same, the last named means including a double check valve operable upon supply of fluid under pressure to either one of said control pipes to open communication therebetween and said adjustable device and to close communication between said adjustable device and the other control pipe.

7. In combination, two fluid pressure supply pipes, two fluid pressure control pipes, two operator's control means each comprising a manually operable lever having a zone of movement, and valve means operable by said lever to supply fluid from one of said supply pipes to one of said control pipes at a pressure corresponding to the position of said lever in said zone, selector means for selectively supplying fluid under pressure to either one of said supply pipes and for at the same time opening the other supply pipe to atmosphere, each control means further comprising repeater means adapted to be operated by fluid under pressure for positioning the respective lever in accordance with the pressure of such fluid, and means associated with each control means operable upon opening to atmosphere the respective fluid pressure supply pipe to open communication between the respective repeater means and the control pipe connected to the other control means and operable upon supply of fluid under pressure to the respective fluid pressure supply pipe to close communication between the respective repeater means and last named control pipe and open the respective repeater means to atmosphere.

8. In combination, two fluid pressure supply pipes, selector means operative to supply fluid under pressure to either one of said supply pipes and to at the same time open the other supply pipe to atmosphere two fluid pressure control pipes, two control devices each comprising a manually operable lever having a zone of movement, and self-lapping valve means operable by said lever to control a communication for supplying fluid from one of said supply pipes to one of said control pipes at a pressure corresponding to the position of said lever in said zone, each control means being also operable upon opening the respective supply pipe to atmosphere to release fluid under pressure from the respective control pipe via said communication.

9. In combination, two fluid pressure supply pipes, two fluid pressure control pipes, two control devices each comprising a manually operable lever having a zone of movement, and self-lapping valve means operable by said lever to control a communication for supplying fluid from one of said supply pipes to one of said control pipes at a pressure corresponding to the position of said lever in said zone, selector means operative to supply fluid under pressure to either one of said supply pipes and at the same time release fluid under pressure from the other pipe, each control means further comprising holding means for holding the respective lever in any selected position, and means open to the respective sup-

15

ply pipe operable upon supply of fluid under pressure thereto to render said holding means effective and operable upon release of fluid under pressure therefrom to render said holding means ineffective.

10. In combination, two fluid pressure supply pipes, two fluid pressure control pipes, two control devices each comprising a manually operable lever having a zone of movement and self-lapping valve means operable by said lever to control a communication for supplying fluid from one of said supply pipes to one of said control pipes at a pressure corresponding to the position of said lever in said zone, selector means operative to supply fluid under pressure to either one of said supply pipes and at the same time release fluid under pressure from the other pipe, each control means further comprising holding means for holding the respective lever in any selected position, and means open to the respective supply pipe operable upon supply of fluid under pressure thereto to render said holding means effective and operable upon release of fluid under pressure therefrom to render said holding means ineffective, and means for restricting release of fluid under pressure from each of said supply pipes and for providing relatively rapid supply of fluid under pressure thereto, upon operation of said selector means.

11. In combination, a fluid pressure adjustable device, a plurality of control means for controlling said device, each comprising a manually operable lever having a zone of movement, self-lapping valve means operable by said lever for supplying fluid under pressure to said device at a pressure corresponding to the position of said lever, and repeater means operable by fluid under pressure to move said lever to a position corresponding to the pressure of such fluid, selector means adjustable to selectively render any one of control means effective to supply fluid under pressure to said device and to at the same time render all other control means ineffective to control said device, and means operable upon operation of said selector means to render any one of said control means effective to control said device to also effect a release of fluid under pressure from the respective repeater means and to supply fluid under pressure from said device to all other repeater means.

12. In combination, two operator's control means each comprising a rockable lever having a zone of movement, self-lapping valve means operable by said lever to supply fluid at a pressure corresponding to the position of said lever, a fluid pressure controlled repeater motor adjustable to a position corresponding to the pressure of such fluid, lever means connecting said motor to said lever for adjusting said lever by said motor, means for conveying fluid under pressure from the valve means in each control means to the repeater motor in the other control means, and means for selectively rendering the valve means in either control means ineffective to supply fluid under pressure and at the same time

16

to render the repeater motor of the other control means ineffective to move the respective lever.

13. In combination, two operator's control means each comprising a rockable lever having a zone of movement, self-lapping valve means operable by said lever to supply fluid at a pressure corresponding to the position of said lever, a fluid pressure controlled repeater motor adjustable to a position corresponding to the pressure of such fluid, lever means connecting said motor to said lever for adjusting said lever by said motor, a fulcrum for said lever means shiftable to one position upon supply of fluid under pressure to said motor to render said motor effective to adjust said lever and operable upon release of fluid under pressure from said motor to render said lever means movable by said lever relative to said motor, means for conveying fluid under pressure from the valve means in each control means to the repeater motor in the other control means, and means for selectively rendering the said valve means in either control means ineffective to supply fluid under pressure and at the same time to release fluid under pressure from the repeater motor and fulcrum means in the other control means.

14. In combination, two operator's control means each comprising a rockable lever having a zone of movement, shelf-lapping valve means operable by said lever to supply fluid at a pressure corresponding to the position of said lever, a fluid pressure controlled repeater motor adjustable to a position corresponding to the pressure of such fluid, lever means connecting said motor to said lever for adjusting said lever by said motor, a fulcrum for said lever means shiftable to one position upon supply of fluid under pressure to said motor to render said motor effective to adjust said lever and operable upon release of fluid under pressure from said motor to render said lever means movable by said lever relative to said motor, means for conveying fluid under pressure from the valve means in each control means to the repeater motor in the other control means, each control means further comprising holding means operable by fluid under pressure to hold the respective lever against accidental movement and rendered ineffective upon release of such fluid under pressure, and means for selectively rendering said valve means in either control means ineffective to supply fluid under pressure and for at the same time releasing fluid under pressure from the respective holding means, and from the repeater motor and fulcrum means in the other control means.
